Patented Dec. 31, 1901.

M. F. PRICE.

MERCHANDISE CHUTE FOR VENDING MACHINES.

(Application filed Nov. 27, 1901.)

UNITED STATES PATENT OFFICE.

MILBERT F. PRICE, OF IOWA CITY, IOWA.

DESIGN FOR A MERCHANTISE-CHUTE FOR VENDING-MACHINES.

SPECIFICATION forming part of Design No. 35,520, dated December 31, 1901.

Application filed November 27, 1901. Serial No. 83,951. Term of patent 14 years.

To all whom it may concern:

Be it known that I, MILBERT F. PRICE, a citizen of the United States, and a resident of Iowa City, in the county of Johnson and State 5 of Iowa, have invented and produced a new and original Design for a Merchandise-Chute for Vending-Machines, of which the following is a specification, reference being had to the accompanying drawings, forming part there- 10 of, in which—

Figure 1 is a front elevation of a merchandise-chute embodying the design. Fig. 2 is a side view thereof, and Fig. 3 is a section on the line 3 3 of Fig. 2.

15 The design comprises a body part made up of a back wall a , side walls b , and front walls c , the front walls being separated from each other to present a slot c' between them. At the bottom of the chute appears a forwardly- 20 extending enlargement, formed of extensions b' of the side walls and an extension a' of the rear wall. The front walls c project downward for a short distance between the exten-

sions b' of the side walls, as shown in Fig. 1. At the top of the chute the front walls c are 25 curved outward, as indicated at c^2 , and the side walls are widened, as at b^2 , to accommodate the front walls.

The leading feature of the design consists in the chute with the body portion substantially as described and the widened end parts 30 a' , b' , b^2 , and c^2 .

Having described my invention, what I claim as new, and desire to secure by Letters Patent, is—

35 The design for a merchandise-chute for vending-machines, as herein shown and described.

In testimony whereof I have signed my name to this specification in the presence of 40 two subscribing witnesses.

MILBERT F. PRICE.
